E. Frank Searle, INVENTOR
BY *Harold D. Basson*, ATTORNEY.

UNITED STATES PATENT OFFICE.

EPHRAIM FRANK SEARLE, OF LAWRENCE, MASSACHUSETTS.

APPARATUS FOR FACILITATING THE CUTTING OF RECESSES IN WALLS.

1,392,360.

Specification of Letters Patent.

Patented Oct. 4, 1921.

Application filed October 23, 1920. Serial No. 419,111.

To all whom it may concern:

Be it known that I, EPHRAIM FRANK SEARLE, a citizen of the United States, residing at Lawrence, in the county of Essex 5 and State of Massachusetts, have invented certain new and useful Improvements in Apparatus for Facilitating the Cutting of Recesses in Walls, of which the following is a specification.

10 My invention relates to devices for the purpose of facilitating the accurate cutting of recesses in walls, especially those formed of laths and plaster, and in locating in such recesses boxes of a type such as those used 15 for housing electric switches. Where such boxes are to be placed in finished walls, whether such walls are papered or painted, on account of the brittle nature of the plaster, there is great danger that it will be 20 broken to a point beyond the area covered by the finishing plate such as is generally used. When a break of this kind occurs, it is impossible to patch it without leaving an unsightly mark.

25 My invention is a device which is useful in the process of cutting such recesses and of locating such boxes therein, and includes a special form of templet for so doing.

30 My device and process save the necessity of marking on the wall the place to be cut, clamps the plaster between a plate and the laths thus preventing vibration and crumbling, and serves to protect the wall from snakes and other tools used by wire workers 35 in fishing and in other processes.

In the drawings, Figure 1 is an elevation showing a wall set of my preferred form with the parts assembled.

Fig. 2 is an elevation showing a section of 40 wall with my templet in position for guiding the cutter tool before the cutting takes place, with part of the plaster broken away to show the position of the laths.

Fig. 3 is an elevation similar to Fig. 2 45 showing the wall after the recess has been cut.

Fig. 4 is an elevation showing a wall with a recess cut with the assistance of my templet, with a box in position held in place by one 50 screw, and a switch of a common type in position in the box.

Fig. 5 is an elevation showing a box and switch in position, all covered by the usual finishing plate.

Fig. 6 is an elevation of a templet without 55 lath screw holes as arranged for cutting a recess to receive three boxes.

Fig. 7 is a sectional detail showing the manner in which I may hold the parts of my 60 wall set in place.

The box G may be of any usual type having 65 projections 32 at opposite corners, and flat thin ears H through each of which are two screw passages 31, 31.

B represents a flat faced templet, shown as 70 being rectangular in form, with a substantially rectangular opening 20 but cut away at 21, 21, of a size to permit the outer edges 30 and projections 32, 32, of box G to pass through.

In templet B are also screw holes 22 in 75 the same relative position to opening 20 as the screw passages 31 are to the face or edge 30 of box G and medial holes 27, 27.

It will be seen that when the set is assembled, the templet B and box G are held together by means of screws F which, as shown in Fig. 7, may be kept in position by rubber washers such as W. Similar rubber washers W may be used to hold screws 28 in position. The ears H should preferably be thin 80 so that a finishing plate, such as shown at M, can be passed over them without being caused to tip. As shown, box G also has 85 projections K in which are threaded holes 33.

For the purpose of cutting a wall recess such as C, Fig. 3, and of working therein, I first place templet B against a wall such as A in such position that the screw holes 22 will be in a location where two of the 90 screw passages, such as 31, will eventually be located. I fasten it firmly in position by screwing the screws F, F, through the holes 22, 22.

With my preferred form, shown in Figs. 95 1, 2 and 3, I also pass screws 28, 28, through lath screw holes 27, 27, in templet B through the plaster R and one of the laths S of the wall A. The templet should be so located 100 that these screw holes 27 will come near the middle of a lath and not opposite the horizontal space between laths. The screws 28, 28, clamp plaster R between the center of the lath S and the templet B, thereby holding the section of that lath between the side 105 walls 20 of the templet firmly in position while the cutting is taking place. This is very desirable for the reason that if the re-

cess is to be cut through a lath close to the joist, the single nail holding the end of the lath is not sufficient to keep it from breaking away during the cutting. Moreover, these screws 28, 28, prevent the vibration of the remaining end of the lath when one side has been cut.

When all the screws 28, 28, F, F, are in position, by means preferably of a key-hole saw or hack-saw blade which is set very little, if any, I cut through wall A around the outlines 20, 21 of the opening of the templet, thereby forming a recess C. The plaster R may be broken away first or I may cut directly through plaster and laths, leaving the templet in position to protect the edges of recess C. I can work to draw in a tube, such as D, or wires 10, 11, or both, with no danger of breaking down the edges 20 of the recess.

When all is in position, I remove the templet B by withdrawing the screws F, F, and 28, 28, and place a box, such as G, in position as shown in Fig. 4, by passing the screws F preferably through two or more of the screw passages 31 into the screw holes in the wall made by the same screws in fastening the templet B in position. A switch L of a common type, having push buttons 30 50 and 51, is then generally placed in the box G, and may be held in position by means

of screws passed through holes 54 into screw holes 33.

The finishing plate M is now slipped over the box and switch, and is held in place by means of screws 62, 62, which pass into threaded screw holes 52, 52, in switch L in a well-known manner.

In Fig. 6, I show a templet P and an opening 70, 71, and screw holes 72 arranged in position to coincide with the respective screw passages in the ears of three boxes. This templet is shown without lath screw holes.

I claim:

1. A templet for an electrical box having ears with screw passages therethrough, which has an opening through which said box except the ears can pass, and screw holes which register with said screw passages.

2. A templet for an electrical box having ears with screw passages therethrough, which has an opening through which said box except the ears can pass, screw holes 55 which register with said screw passages, and lath screw holes medially located between the top and bottom.

In testimony whereof I have affixed my signature.

E. FRANK SEARLE.
